FLUID SYSTEM AUTOMATIC VENT VALVE

Julius Hulman, Dayton, Ohio

Application September 4, 1944, Serial No. 552,663

3 Claims. (Cl. 277—60)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to fluid pressure systems, of that class in which a fluid is required to be maintained under a substantially constant pressure by a pumping or similar means, and more particularly to a means for separating air or vapor from the oil or other liquid which is being pumped.

In systems of this character, particularly wherein the pump of the system has its suction or low pressure side connected to a supply tank or reservoir from which it takes fluid and discharges it into the high pressure side of the system, it happens frequently and for various reasons that air or vapor gets into the liquid and the system becomes air or vapor locked. If the amount of air or vapor is minute, the pump may discharge it into the high pressure side, which will of course cause the pressure in the high pressure side to drop but not enough to result seriously. However, if the volume of air or vapor entering the pump is larger, the pump may lose its prime. Moreover, if the system is one of that type wherein a plurality of pumps are connected in parallel, and are provided with check valves biased to prevent return of fluid from an operative pump backward through a disabled pump, a pump which has lost its prime will not regain it, in which case the unprimed pump may be permanently disabled, particularly if the liquid in the system is depended on for lubrication of the pumps.

It is therefore an object of this invention to provide, in a system of this kind, a simple, inexpensive and effective means to arrest air or vapor coming through the pump from the suction side to the discharge side, and return it to the vented interior of the supply reservoir without passing it into or through the high pressure side of the system.

More specifically stated it is an object of the invention to retain the conventional check valve, which is usually placed between the discharge side of the pump and the remainder of the high pressure side of the system to prevent the return of the fluid under pressure through the pump, but supplement this conventional check valve with a vent valve which opens in response to a drop in pressure at the upstream side of the check valve caused by air or vapor being pumped from the suction to the discharge side.

Other objects and advantages will become

evident from the following detailed description when considered with reference to the drawing, wherein:

Fig. 1 is a longitudinal axial sectional view through the improved valve structure which is adapted to be connected to, or to extend integrally from the discharge side of the fluid pump of the system, the vent valve being shown in the closed position.

Fig. 2 is a longitudinal axial section through the vent valve when it is in the open position.

Fig. 3 is an end view of the device shown in Fig. 1.

Fig. 4 is a longitudinal axial section through a modified form of vent valve.

Fig. 5 shows a further modification of the vent valve.

In the drawing, a valve body 10 which normally houses only a check valve 12 is here provided with a bulge 14 to contain also the vent valve 16.

The check valve 12 comprises a triangular valve head 18 beveled at 20 for engagement with the valve seat 22 at the right hand end of the main fluid conduit 23, and having the three points 24 of the triangle slidable freely in a bore 26 of the body 10. A spring 28 is biased to hold the head 18 on the seat 22, the spring being held under an initial stress by a threaded plug 30 which is provided with a series of holes 32 through which fluid coming through the valve 12 may pass.

The vent valve 16 comprises a casing 34 which is snugly fitted to a bore 36 in the bulge 14. A part 38 of the casing 34 is externally threaded to fit into corresponding internal threads in the housing 10, whereby the casing is held in place in the housing. Seal rings 40 prevent leakage of fluid between the casing 34 and the bore 36.

The casing 34 is provided with a bore 42 within which a small piston 44 is axially slidable. The bore 42 is open at the right end and closed at the left as shown. A spacing tube 46 is provided to limit movement of the piston 44 to the left

while the end wall of the bore 36 limits its movement to the right. A light spring 48 surrounding the tube 46 is just sufficient to hold the piston 44 to the right end of its travel as shown in Fig. 1, except when the vent valve becomes active to eliminate air or vapor in which case it moves to the position shown in Fig. 2.

A passageway 50 connects the main passageway 23 to an annular groove 52 surrounding the casing 34, and several small holes 54 connect the groove 52 to the space between the coils of the spring

48. Several small holes 58 pass through the wall of the spacing tube to join the inside of the spacing tube to a passageway 58 centrally disposed in the piston 44. Several small radial holes 60 connect the passageway 58 to an annular groove 62 which surrounds the piston. Several radial holes 64 connect the annular groove 62 to an annular groove 66 which surrounds the casing 34. A vent opening 68 communicates with the groove 66 and is threaded as at 70 for pipe connection to the vented top of the fluid reservoir of the system. A passageway 72 connects the bore 42 of the casing 34 to an internal annular groove 74 in the bore 28 whereby the right hand end of the piston 44 is at all times exposed to the pressure in the space 76 which is a part of the high pressure side of the system.

The operation of the device shown in Figs. 1, 2, and 3 is as follow:

During normal operation of the system, fluid flows from the discharge side of the pump of the system through the conduit 23 and valve 12 into the chamber 76 and into the piping or containers which constitutes the high pressure side of the system. There will be a slight pressure drop from the conduit 23 to the chamber 76, the amount of drop depending mainly on the strength of the spring 28. Since the pressure in conduit 23 acting through the passageway 50 exceeds the pressure of chamber 76 acting through passageway 72, the normal tendency of the piston 44 is to move to the right. This tendency is slightly augmented by the light spring 48 if this spring is used. It is noted, however, that while use of the spring 48 is desirable, it may be eliminated without seriously affecting the operation of the device. As long, therefore, as no air or vapor comes from the discharge side of the pump into the conduit 23, the device will remain in the condition shown in Fig. 1.

If, however, any substantial volume of air or vapor is discharged by the pump into the conduit 23, a sharp pressure drop in the conduit 23 will take place, because of the fact that the air or vapor requires a great reduction in volume and therefore considerable pumping effort to raise the pressure of the air or vapor to that of the liquid in the chamber 76.

When then, due to air or vapor being brought into the conduit 23, the pressure in conduit 23 drops far enough below that in the chamber 76 to slightly more than balance the effort of the light spring 48 or to overcome the friction of the piston 44 in its bore, if the light spring 48 is not used, the piston 44 will move to the left as in Fig. 2 and the air or vapor will pass through the passageways 50, 52, 54, 56, 58, 60, 62, 64, 66, and 68 back to the vented top of the supply reservoirs from which fluid is being pumped.

With the air or vapor thus eliminated, the pressure will rise rapidly in the conduit 23, and, as soon as this pressure, plus the effort of the spring 48, if used, exceeds the pressure in the chamber 76, the piston 44 will return to the normal position shown in Fig. 1 where the vent valve 16 is closed.

As a more concrete example of the operation of the device of Figs. 1, 2 and 3, let it be assumed that an unloading valve or relief valve downstream of the check valve 12 is set to maintain a pressure in the chamber 76 of 1000 lbs.; that the check valve spring 28 is under a stress of 10 lbs. in which case the pump being used must have capacity to raise the pressure in conduit 23 to

slightly over 1010 lbs., and that the light spring 48 is under a stress of 2 lbs.

If a sufficiently large volume of air or vapor now enters the conduit 23, the pressure in conduit 23 may drop as low as 500 lbs. When this happens, the 1000 lb. pressure in chamber 76 will move the piston 44 to the left, as in Fig. 2, thus opening the vent passage 60.

As the pump continues to operate, the air will 10 first be discharged through the vent 60-68, or, if the air is admixed with the hydraulic fluid, the mixture will pass through the vent opening 60. It should at this point be noted that the vent 60, or some other part of the channel through 15 which the air must pass, must be of such size, with respect to the capacity of the pump that, as long as air, or mixed hydraulic fluid and air is passing out the vent 60 the pump can not build up pressure in the conduit 23, great enough 20 to close the vent valve, but when the air or mixture has all been discharged, and the pump is again pumping the heavier medium, the pump can build up pressure in the conduit 23 sufficient to close the vent valve in spite of the leakage 25 through the vent 60.

When the pressure in the chamber 23 is thus built up to 999 lbs., this pressure, plus the 2 lb. stress of the spring 48, if the spring 48 is used, making 1001 lbs. pressure urging the piston 44 to 30 the right, and since the pressure in the chamber 76 is only 1000 lbs. the piston 44 moves to the right and closes the vent 60.

Since the pressure in conduit 23 is now only 999 lbs. and the pressure in chamber 76 plus the 35 spring 28 is 1010 lbs. the check valve is still closed, but several additional seconds operation of the pump will make up this deficiency and the check valve 12 will open and the system be back to normal.

40 In the modification shown in Fig. 4, the bulge 14 is bored as at 78 and provided at the closed end of the bore with an inserted valve cage 80, the outer end of the bore being closed by a screw plug 82.

45 The valve head 84 has a seat 86 in the cage 80 and an integral stem 88 which is slideable in a bearing 90 in the cage. An annular space 91 surrounds the stem 88 near one end and an annular chamber 93 surrounds the stem near the 50 other end. The space 91 may be connected by a groove 95 to the chamber 93 and the chamber 93 to the atmosphere through the opening 88, or the groove 95 may be omitted if the bearing 90 is slightly loose on the stem 88. A diaphragm 55 92 has its central portion secured to the stem 88 by a nut 94 and its perimeter secured to the cage 80 by a hollow externally screw-threaded plug 96. A light compression spring 98 may be held under an initial stress between the plug 82 60 and the valve head 84 in the chamber 100, or the spring may be omitted and the pressure in the chamber 100 relied upon to close the valve. As long as the pressure entering the chamber 100 at 50, plus the pressure of the small spring 98, 65 if used, is greater than the pressure entering at 72 and acting on the diaphragm 92, the valve head 84 will remain on its seat 86. The entry of an amount of air or vapor that will cause the pressure to drop to an extent where the pressure 70 in the chamber 100 plus the pressure of the light spring 98 is less than the pressure entering at 72, will cause the valve head 84 to rise from its seat 86 and permit the air to escape through the vent 68.

75 In the modification shown in Fig. 5, the bulge

14 is fitted with a casing 77, the bore of which is stepped, having a larger portion 79 and a smaller portion 81 to which a stepped piston 83 is slidably fitted. With the exception of being stepped, the piston 83 is like that shown in Fig. 1, having an axial opening 58, transverse openings 60, the annular groove 62, the vent opening 68 and the threaded portion 10. Additionally the space 85 adjacent the step in the piston is carried through a passageway 87 to the vent 68-70. A spring 89 urges the stepped piston toward the right to the closed-vent position shown.

With the left end of the piston 83 having a greater area exposed to pressure than the right end, it is obvious that the valve will shift to the closed position shown when the pressure on the left or upstream side of the piston is still much below that of the downstream side. Under this condition, the vent passages 58, 60, 68, etc., must be of such size or be so restricted that the air or mixture of oil and air will all have passed out through the vents before the pumped pressure shifts the valve. Thereafter a relatively short period of additional pumping into the passageway 23 will be required to reach a pressure which will open the valve 18, the period depending, of course, on the amount of step in the piston 83.

While in the several exemplifications of the invention shown, springs are used in both the check valve and the vent valve for urging them to the closed positions, it is obvious that the springs in both cases may be omitted and the valves be closed by the pressure alone, since the pressure in the conduit 23 exceeds that in the chamber 76 when no air or vapor is present in the conduit 23, whereas the pressure in the chamber 76 exceeds that in the conduit 23 where air or vapor enters the conduit.

It is further noted that in both examples shown the vent valve is made as a separate unit and inserted into the main valve body 10, it is obvious, however, that the vent valve casing 34 or valve cage 80 could be made an integral part of the body 10.

Having described several embodiments of my invention in which the objects set forth are attained, I claim:

1. A valve mechanism comprising a body hav-

ing a flow passage therethrough with upstream and downstream ends adapted respectively to receive and discharge a hydraulic fluid under pressure, a check valve in said flow passage intermediate said ends biased to prevent flow from said downstream and back to said upstream end, an opening connecting the flow passage upstream of the check valve back to the flow passage downstream of the check valve, said opening including a cylindrical portion, an air vent in the wall of said cylindrical portion, a piston in said cylindrical portion slidably downstream in said cylindrical portion to a vent closing position when the pressure in the upstream end exceeds the pressure in the downstream end and slidably upstream in said cylindrical portion to a vent opening position when the pressure in the upstream end falls below the pressure in the downstream end, a spring urging said check valve to the closed position, whereby the pressure in the upstream end normally exceeds the pressure in the downstream end, the upstream end of said piston having at least as large an area as the downstream end, whereby the pressure in the upstream end must fall below the pressure in the downstream end before the vent valve can open.

2. The device of claim 1 in which the upstream end of the piston has a larger area than the downstream end.

3. The device defined in claim 1 in which there is a second spring urging the piston toward the downstream end, and in which the force of said second spring taken together with the force of the pressure acting on the upstream end of the piston normally exceeds the force of the pressure acting on the downstream end of the piston, whereby the vent is opened only when the upstream pressure falls below the downstream pressure.
